H. L. BASSETT

SHOVEL HANDLE

Filed Jan. 29, 1923

INVENTOR.
HENRY LEE BASSETT,

BY

G. B. Schley,
ATTORNEY.

UNITED STATES PATENT OFFICE.

HENRY LEE BASSETT, OF COLUMBUS, INDIANA.

SHOVEL HANDLE.

Application filed January 29, 1923. Serial No. 615,661.

To all whom it may concern:

Be it known that I, HENRY LEE BASSETT, a citizen of the United States, residing at Columbus, in the county of Bartholomew and State of Indiana, have invented a new and useful Shovel Handle, of which the following is a specification.

It is the object of my invention to provide a satisfactory sheet-metal head for a D-handle, which sheet-metal head with its grip will be an acceptable substitute for the wooden D-handle, has a non-turning grip, is rigid with the stale, is made wholly of two sheet-metal stampings which are preferably welded together at their stale-engaging parts to form a tubular socket, and has the appearance as well as the comfort of the wooden D-handle and is much stronger.

I am aware that many attempts have been made to make D-handle heads of sheet-metal, but these have been costly to make, or have not proved effective in use from the standpoint of wear and strength, and have not had the satisfactory "feel" obtained from the wooden D-handle.

By my invention, I largely if not wholly overcome these difficulties.

The accompanying drawing illustrates my invention: Fig. 1 is an edge elevation of a handle embodying my invention, with a fragment of the stale; Fig. 2 is a front elevation, in partial section on the line 2—2 of Fig. 1; Fig. 3 is an elevation, from the inside, of one of the sections of my D-handle head, before it is welded to its mate, and before the grip is inserted; Fig. 4 is a plan of the D-handle head, but with the grip in dotted lines; and Fig. 5 is a reduced plan of a blank sheet-metal stamping from which each section of my D-handle head may be made.

My D-handle head is made of two sheet-metal sections A and B. These sections are identical, so that the complete D-handle head may be made by putting any two sections together. Each section is made as an integral sheet-metal stamping, from a blank such as shown in Fig. 5, which is suitably shaped on the press to form the final section. The blank may be considered as formed of three parts, 10', 11', and 12', all integral with each other. The lower part 10' is formed into a semi-tubular shell or half-socket 10, of the proper size and shape to fit the upper end of the stale 13. This semi-tubular shell or half-socket 10 is preferably

slightly conical or tapered, to fit on the correspondingly tapered end of the stale.

The intermediate part 11' of the blank is shaped in the press to form a curved arm 11, which branches from the upper end of the shell 10 in an outward and upward curve, concave upward and inward, with the two edges 14 of the blank-part 11' folded in toward each other and in the same plane so that they meet or substantially meet, and with the longitudinal middle part of the blank 11' curved into an arc-shaped cross-section, as is clear from the dotted lines at either end of Fig. 4. This makes the cross-section of the arm approximately D-shaped, with the flat part inward and the curved part outward, and also serves to form a structure of great strength. In order further to strengthen this structure, the part 11' of the blank is made wider at its lower end, near the shell-forming part 10', so that the finished arm 11 will be both wider and much thicker near the stale than it is near the grip, as is the case with the wooden D-handle.

The part 12' of the blank is in the general form of a disk, and in the shaping operation the edges of this disk are turned inward to form a circular grip-socket 12, of which the turned-in edges 15 form the side walls. The base of the socket 12 is provided with a hole 16 through it, preferably on the medial line of the section but displaced from the center of the socket 12 toward the arm 11 so that it is eccentric with respect to the socket.

In assembling the device, two identical sections A and B are placed together with the edges of their half-round shells 10 abutting, to form a complete tubular socket for fitting on the upper end of the stale 13, both stale-end and shell preferably being tapered. The abutting edges of the shells 10 and arms 11 are preferably butt-welded together, to form a seamless socket for the stale-end. This socket is placed on the end of the stale, preferably with a driving fit, and attached thereto by cross rivet 17, of which one is usually sufficient. When placing the two sections A and B together, and before such sections are welded together, the two ends of a wooden grip 18 are placed in the two grip-sockets 12 of the two sections, which sockets are opposite each other. This grip 18 is preferably shaped like the grip of a wooden D-handle, being in general round in cross-section, but relieved on the under side,

2
as shown in Fig. 2, for the sake of giving a better grip. The upper surface of the grip preferably curves convexly from one socket to the other. The grip is held from turning 5 from its proper position in the grip-sockets 12 by a cross-pin 19 which extends lengthwise through an eccentric hole in the grip 18 and through the holes 16 in the bases of the sockets 12, with which holes 16 the hole 10 in the grip is alined. The ends of the pin 19 are conveniently riveted to lock the structure together.

Preferably, to provide smooth surfaces, the grip 18 and the stale 13 are both shouldered where they fit into their respective 15 sockets, so that the outer surfaces of the socket will be flush with the outer surfaces of the wooden members which they receive.

In operation, this sheet-metal D-handle 20 head acts and "feels" like a wooden D-handle. The grip 18 does not twist in the hand any more than does the integral grip of a wooden D-handle. The arms 11 are properly shaped to stand the stresses to which they 25 are subjected at different points, because they are of larger cross-section near the stale than near the grip. The bent-over edges which form the inner surface of the arms 11 overlie the end surface of the stale 13, as 30 is clear from Fig. 2, and may abut such end surface to assist in the transmission of force from the D-handle head to the stale; but such force is in the main transmitted by the tapered fit of the socket on the stale and 35 by the shoulder 20 against which the end of the stale-receiving socket abuts, and by the cross rivets 17. The inner surfaces of the arms 11, by reason of this overlapping of the bent-over edges 14 upon the end surface 40 of the stale 13, form a smooth continuous curve over the stale-end from one socket 12 to the other.

I claim as my invention:

1. A sheet-metal D-handle head, comprising 45 two sections each made as a stamping of sheet-metal, each of said sections comprising a curved tubular arm provided at one end with a grip-socket and at the other end with a stale half-socket, said two parts being put together so that the edges of the stale half-sockets meet to form a complete stale-socket and the two grip-sockets are opposed to each other.

2. A sheet-metal D-handle head, comprising 55 two sections each made as a stamping of sheet-metal, each of said sections comprising a curved tubular arm provided at one end with a grip-socket and at the other end with a stale half-socket, said two parts 60 being put together so that the edges of the

stale half-sockets meet and are welded together at both meeting edges to form a complete seamless stale-socket, and the two grip-sockets are opposed to each other.

3. A sheet-metal D-handle head, comprising 65 two sections each made as a stamping of sheet metal, each of said sections comprising an arm provided at one end with a grip-socket and at the other end with a stale half-socket, said two sections being put together so that the stale half-sockets mate and the grip-sockets oppose each other, the arm of each section being folded from sheet-metal to form a tube of substantially 70 D-shaped cross section.

4. A sheet-metal D-handle head, comprising 75 two sections each made as a stamping of sheet-metal, each of said sections comprising a tubular arm provided at one end with a grip-socket and at the other end with a stale half-socket, said two sections being put together so that the stale-sockets mate and the grip-sockets oppose each other, the arm of each section being formed from a strip of sheet-metal with the edge portions 80 bent toward each other into substantially the same plane, said edge portions being arranged to overlie the upper end of the stale-socket to form a base for said stale-socket.

5. A sheet-metal D-handle head, formed 85 with a stale socket, and two tubular arms diverging from said stale-socket and provided at their other ends with opposed grip-receiving sockets, said arms being of tapering cross-section largest near the stale-socket.

6. A sheet-metal D-handle head, formed 90 with a stale socket, and two tubular arms diverging from said stale-socket and provided at their other ends with opposed grip-receiving sockets, said arms being formed of sheet-metal folded into D-shaped cross-section with the longitudinal edges opposing 95 each other along the inner face of the arm.

7. A sheet-metal D-handle head, formed 100 with a stale socket, and two tubular arms diverging from said stale-socket and provided at their other ends with opposed grip-receiving sockets, said arms being formed of sheet-metal folded into D-shaped cross-section with the longitudinal edges opposing 105 each other along the inner face of the arm, the cross-section of each arm being tapering with the largest cross-section close to the stale-socket.

In witness whereof, I have hereunto set my hand at Columbus, Indiana, this 24th day of January, A. D., one thousand nine hundred and twenty three.

HENRY LEE BASSETT.
